KNOCKDOWN TABLE

Robert T. Howitt, Leominster, Mass.

Filed Oct. 10, 1973, Ser. No. 405,018

Term of patent 14 years

Int. Cl. D6—03

U.S. Cl. D6—176

FIG. 2

FIG. 5

FIG. 6

FIG. 1 is a perspective view of a knockdown table embodying the principles of the present invention,

FIG. 2 is a perspective view of the table in an inoperative condition,

FIG. 3 is a plan elevational view of the table top,

FIG. 4 is a longitudinal sectional view of the table top taken on the line IV—IV of FIG. 3,

FIG. 5 is a sectional view of a leg,

FIG. 6 is an elevational view of the leg, and

FIG. 7 is a transverse sectional view of the leg.

I claim:

The ornamental design for a knockdown table, as shown.
